(57) **CLAIM**

The ornamental design for a pacifier simulative of an elephant, as shown and described.

DESCRIPTION

FIG. 1 is a front elevational view of a pacifier simulative of an elephant, showing our new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a rear elevation view thereof;

FIG. 7 is a top, rear perspective view thereof; and,

FIG. 8 is a top, front perspective view thereof.

The broken lines shown in the figures are for the purposes of illustrating portions of the pacifier simulative of an elephant that form no part of the claimed design.

1 Claim, 3 Drawing Sheets
